(57) **CLAIM**

The ornamental design for a holder with a transparent panel/section and holder with an opaque panel/section, as shown.

DESCRIPTION

FIG. 1 is a perspective view of a holder with a transparent panel/section showing my new design according to a first embodiment;

FIG. 2 is an exploded perspective view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view thereof;

FIG. 8 is a rear elevational view thereof; and

FIG. 9 is a perspective view of a holder with an opaque panel/section showing my new design according to a second embodiment;

FIG. 10 is an exploded perspective view thereof;

FIG. 11 is a top plan view thereof;

FIG. 12 is a bottom plan view thereof;

FIG. 13 is a right side elevational view thereof;

FIG. 14 is a left side elevational view thereof;

FIG. 15 is a front elevational view thereof; and,

FIG. 16 is a rear elevational view thereof.
